ROTARY BLOTTER

Filed June 7, 1929

Inventor:

Charles Hamilton Pajeau

By Albert Scheibh
Attorney.

UNITED STATES PATENT OFFICE

CHARLES HAMILTON PAJEAU, OF GLENCOE, ILLINOIS, ASSIGNOR TO THE TOY TINKERS, INC., OF EVANSTON, ILLINOIS, A CORPORATION OF ILLINOIS

ROTARY BLOTTER

Application filed June 7, 1929. Serial No. 369,048.

My invention relates to so called rotary blotters, namely blotting appliances in which the absorbent blotter is disposed as a cylindrical surface and adapted to be rolled over the paper on which the ink is to be blotted.

With such rotary blotters, the absorbed ink gradually spoils the effectiveness of the outer blotting surface, so that provision must be made for presenting fresh blotter parts, unless the effective use of the rotary blotter is to be limited to so short a period of time as would be out of proportion to the cost of the blotting appliance. For this purpose, it has heretofore been customary to mount a series of concentrically curved blotters on a carrier roll, but the arrangements for rigidly securing the consecutive blotters to each other and to the roll have been such as to produce non-absorbent or rough portions on the successively exposed blotters, or have caused parts of the exposed blotter to project radially beyond other parts, or otherwise have involved a damaging of the freshly exposed blotter.

Furthermore, the rotary blotters as heretofore proposed have included manipulating means—usually in the form of forks carrying handles—which project far beyond the rotary blotter portion. Such bulky manipulating means not only greatly increase the cost of the blotting appliances and the space required for storing the same, but also undesirably increase the size and cost of the cartons needed for shipping them.

My present invention aims to overcome all of these objections, and in its general aspects includes these objects:

(1) Providing blotter manipulating means which will require scarcely any space beyond that needed for the blotters and which will permit a convenient handling of the blotting appliance.

(2) Providing blotter-securing means which will permit each of a plurality of blotters to present a complete and substantially cylindrical blotting surface and which will not impair the surface of adjacent blotters.

(3) Providing blotter-securing means so arranged that they can easily be ruptured by the insertion of any small pointed objects be-

tween the abutting ends of the blotter with which the securing means are associated.

(4) Arranging the securing means for the concentric blotters so that they will not materially affect the cylindrical shape of the exposed blotting surfaces.

(5) Providing a simple and inexpensive method of assembling the thus secured blotters on a carrier roll.

(6) Providing a novel carrier roll construction for rotary blotters.

Still further and also more detailed objects will appear from the following specification and from the accompanying drawings, in which

Fig. 1 is an end view of a rotary blotter embodying my invention.

Fig. 2 is a plan view of the same rotary blotter, with dotted lines showing portions of a hand as it appears when manipulating the rotary blotter.

Fig. 3 is a central section taken longitudinally of the same rotary blotter, along the line 3—3 of Fig. 1.

Fig. 4 is an enlarged transverse section, taken along the line 4—4 of Fig. 2.

Fig. 5 is a side elevation of the parts of the abutting end portions of one of the blotter tubes, with dotted lines showing the sealing strip which connects these ends.

Fig. 6 is an interior elevation of the same blotter parts as Fig. 5.

Fig. 7 is an enlargement of the upper portion of Fig. 4, showing the use of a pin point for rupturing one of the sealing strips.

Fig. 8 is a perspective view, showing the inner tube with an adhesive strip laid on it, and with a blotter sheet ready to be affixed to the adhesive strip.

In the illustrated embodiment, my rotary blotter includes as its carrier member a cylindrical tube 1 (which may be of thick paper) clamped between two metal end pieces through which a central shaft 2 extends. Each of these end pieces has its main and inner portion 3 offset inwardly of the carrier member and connected to its flat annular edge portion 4 by a tubular portion 5 which fits tightly into the adjacent end of the tube 1, and each end piece has a central perforation 90 95 100.

through which the shaft 2 projects. Fitted on each projecting end of the shaft 2 and coaxial with the shaft is a knob 6 which desirably has its outer end face concaved, so as to afford a good fingerhold.

Surrounding the roll 1 are a plurality of blotter tubes, the inner of which (blotter 7) snugly houses the roll, while each of the other blotter tubes (8, 9, 10) snugly houses the blotter tube inside it. Each of these blotter tubes consists of a sheet of blotting paper corresponding in length to the circumference of the surface surrounded by it, this sheet being curved so that the ends of the sheet abut against each other.

To retain each blotter in such curved disposition, I dispose a strip 11 of thin paper between the end portions of the blotter and the surface around which the blotter is wrapped, and paste this strip to the said end portions of the blotter; however, I leave the said strip unsecured to the surface around which the blotter is wrapped, as for example by employing a paper strip which is gummed only on its outer face.

To manufacture the rotary portions of my blotting appliances economically, I desirably start with stiff paper tubes and gummed paper strips many times as long as one of the proposed rolls, and with blotter sheets of corresponding width. Then I lay one gummed paper strip 11 on the tube 1 as shown in Fig. 7, with the gummed face of the strip upward and moistened and with the strip extending longitudinally of the said tube. Next I wrap the inner blotter 7 around the tube so that its end portions both overlap the gummed strip and abut against each other, and press these end portions tightly against the gummed strip. With the next blotter 8, I proceed in a similar manner, but start with a gummed strip 11A seated on the blotter previously clamped upon the tube, and preferably with this second strip 11A displaced rotationally of the roll by a considerable angle from the previously applied strip 11. By thus distributing the successive strips 11 rotationally of the tube 1, and by preferably disposing these strips in uniformly spaced locations, and by also employing thin paper for the strips, I produce a long blotting roll assembly in which the interposing of these strips does not materially alter the cylindrical exterior shape of the faces of the blotters.

This roll assembly is then cut to the desired lengths, to each of which the two end caps, the shaft and the two manipulating knobs are attached as shown in Fig. 3. When my appliance, as thus assembled, is to be used, the two knobs 6 are gripped by the user, desirably between the thumb 12 and the middle finger 13 of one hand, as shown in Fig. 2. The concaving of the outer knob ends not only makes this fit the finger tips readily, but also

insures a gripping of a considerable surface portion by each finger tip, thereby making it easy for the user to lift and to roll my rotary blotter while only lightly gripping these knobs. Thus constructed, my assembled appliance requires hardly any more packing space than the blotter roll alone, as I avoid the need of the heretofore employed forked handles, and my blotting appliance also occupies only a small space in a desk drawer.

By forming each of the concentric tubular blotter members from a sheet of blotting paper corresponding in length to the circumference of the surface around which that sheet is wrapped, I permit the ends of the sheet to abut, so that the resulting tube presents no gap of sufficient width to interfere with an effective blotting of ink by the end portions of the blotting sheet. However, the minute longitudinal gap at the outer surface of each blotter tube (between the ends of the blotter sheet from which that tube was formed) affords a guide for indicating the position of the retaining strip which is gummed to the inner face of that sheet.

When the outer blotter tube has served its purpose, the retaining strip associated with it can readily be cut or torn by inserting any thin and sharp object (such as the tip of a knife blade, pin or needle) in this gap, after the manner shown in Fig. 7, and moving this cutting or tearing tip for the entire length of the gap (or effective slit) in the blotter tube. In practice, each paper retaining strip can be both thin and frail, so that it can be severed in this manner with so light a pressure as not to cause any material indenting of the blotter which is inward of the strip; and as soon as the used blotter tube has thus been severed, it readily springs open and slips off the remainder of the blotting roll.

To insure a longitudinal centering of the blotting roll on the carrier member, I desirably make each of the metal end pieces of a diameter slightly greater than that of the carrier tube 1, so that these ends will extend alongside the innermost blotter tube 7 for a part of the thickness of the latter. By assembling the gummed strips and the blotter sheets on the tubing as heretofore described, I can readily draw the ends of each blotter sheet toward each other, so that the resulting blotter tube tightly surrounds the next inward blotter tube and clamps a retaining strip between them, thereby insuring a rigid assembly.

For use in the average hand, I desirably provide my blotter tubes in a length (or effective blotting width) not exceeding about two inches and desirably have the knobs 6 project slightly longitudinally of my rotary blotter beyond the end pieces. I also desirably wedge these knobs on the shaft 2 and leave the shaft free to rotate in the said end pieces, so that the shaft and knobs remain as a rigid

unit during the rolling of the exposed blotting surface over a paper which is to be blotted.

However, I do not wish to be limited to these or other details of the construction and arrangement above disclosed, since many changes might be made without departing either from the spirit of my invention or from the appended claims.

10 I claim as my invention:

1. A rotary blotter comprising a carrier having a cylindrical outer wall, a plurality of blotters successively wrapped around the said carrier wall, each blotter presenting a cylindrical outer face and having its ends in abutting relation to each other, and retaining strips each extending across the abutting end portions of one of the blotters interiorly of that blotter and secured only to that blotter.

20 2. A rotary blotter comprising a carrier having a cylindrical outer surface, a rupturable strip of material bearing against the said outer surface but not secured to the carrier, and a blotter curved around the body and having its end portions abutting against each other and secured to the outer face of the said strip.

30 3. A rotary blotter comprising a carrier having a cylindrical outer surface, a plurality of blotters consecutively surrounding the said outer surface, each blotter having its ends abutting, the juncture of the ends being out of alignment in consecutive blotters, and retaining strips each secured only to the inner faces of both end portions of one of the blotters.

40 4. In a rotary blotter, a blotter-carrier member comprising a cylindrical tube of a length readily spanned by two fingers of a human hand, two centrally perforated end caps respectively tightly fitted into the ends of the tube, a shaft extending through the central perforations in the end caps and rotatable in the said caps, and knobs respectively mounted on the ends of the shaft exteriorly of the end caps.

50 5. In a rotary blotter, a blotter-carrying member comprising a cylindrical tube; two centrally perforated end caps each including a tubular portion fitted into one end of the tube and a rim portion engaging one end of the tube, and a head extending across the inner end of the tube, a shaft extending through the central perforations in the end caps and rotatable in the said caps; and knobs respectively secured to the ends of the shaft exteriorly of the end caps, each knob bearing against the head of one cap, whereby the two knobs hold the shaft against longitudinal sliding.

60 6. A rotary blotter comprising a substantially cylindrical carrier member, a paper strip bearing against the cylindrical surface of the carrier member and extending longitudinally of the carrier member and having

a non-adhesive inner surface, and a blotter wrapped around the carrier member and presenting abutting end portions overlapping and being pasted to the outer face of the paper strip; a second paper strip bearing 70 against the outer face of the blotter and spaced circumferentially of the carrier member from the abutting ends of the blotter; and a second blotter wrapped around the first named blotter and having its end portions 75 abutting each other, the said end portions of the second blotter overlapping and being pasted to the second strip.

7. A rotary blotter comprising a substantially cylindrical carrier member; concentric 80 blotters wrapped around the cylindrical surface of the carrier member and each having its ends abutting, the lines along which the ends of consecutive blotters abut being spaced circumferentially of the carrier member; and retaining members each comprising a rupturable strip of paper extending across and adhesively secured to the inner faces of the abutting end portions of one of the blotters.

8. A rotary blotting appliance comprising 90 a plurality of concentric and contiguous tubes; each tube consisting of a flat blotter curved to present its tips in abutment, and a relatively thin strip of paper pasted to and overlapping the inner faces of the ends of 95 the blotter.

9. A rotary blotting appliance comprising a plurality of concentric tubes of blotting paper consecutively and snugly housing one another, and a roller snugly housed by the innermost of the said tubes; each of the concentric tubes comprising a sheet of blotting paper curved to present its tips in abutment and a strip of paper adhesively secured to the inner faces of both ends of the said curved sheet; each such strip being clamped, by the tube of which it forms a part, to the element snugly housed by that tube, but being otherwise unsecured to such snugly housed element.

10. In a rotary blotting appliance, a blotter-carrying member comprising a cylindrical tube, two centrally perforated end caps respectively fitted into the ends of the tube and each presenting its cap head longitudinally inward of the tube from the adjacent end of the tube; a shaft extending through the central perforations in the end caps and rotatable in the said caps; and knobs respectively mounted on the ends of the shaft exteriorly of and respectively adjacent to the end caps, each knob presenting its outer end beyond the outer faces of the adjacent end cap; the said knob ends being so spaced as to be grasped by the thumb and a finger of one hand of the user, so that the said shaft and knobs will serve as the sole means for lifting and manipulating the appliance.

11. A rotary blotting appliance comprising 130 a plurality of concentric tubes of blotting

paper consecutively and snugly housing one another; a roller snugly housed by the innermost of the said tubes, the roller including end portions projecting radially of the roller alongside the ends of the innermost tube for a distance less than the thickness of that tube; and knobs projecting axially of the roller beyond the ends of the said tubes, the knobs being rotatable with respect to the roller.

10 Signed at Evanston, Illinois, May 29th, 1929.
